UNITED STATES PATENT OFFICE.

BURDETT P. HOPKINS, OF CLINTONVILLE, WISCONSIN.

PNEUMATIC EJECTOR-PUMP.

1,333,713.

Specification of Letters Patent. Patented Mar. 16, 1920.

Application filed March 24, 1919. Serial No. 284,796.

To all whom it may concern:

Be it known that I, BURDETT P. HOPKINS, a citizen of the United States, residing at Clintonville, county of Waupaca, and State 5 of Wisconsin, have invented new and useful Improvements in Pneumatic Ejector-Pumps, of which the following is a specification.

My invention relates to improvements in 10 pneumatic ejector pumps.

The object of my invention is to provide a form of construction which can be installed in drive wells, or in any other tubular well, and which can be manufactured 15 at small cost, the number of parts being reduced to a minimum.

In the drawings:

Figure 1 is a vertical sectional view of a 20 drive well tube in position for use, and showing my improved ejector, partly in vertical section and partly in elevation.

Fig. 2 is a sectional view, drawn on line 2-2 of Fig. 1.

Like parts are identified by the same reference characters throughout both views.

A is an ordinary drive well tube, provided with the customary drive point B. This tube, however, is capped at the top with an air tight cap C, through which the vertically disposed water pipe D passes. E is an ordinary shell or pumping head.

Near the lower end of the well tube A, I provide a tubular chamber F, the top of which is provided with a cap plug G into 35 which the lower end of the water discharge pipe D is screwed, or otherwise secured. A duct H extends downwardly through the plug G, and is provided with a double elbow within the chamber F, as indicated at h, h', 40 the other end of this duct H extending upwardly for a short distance into the inlet end or lower end of the tube B, in the form of an upwardly projecting nozzle I. It will be observed that the duct H is therefore substantially a U-shaped pipe, one end of which extends through an aperture in the plug G, and the other end of which constitutes the nozzle I.

At the lower end of the chamber F it is 50 provided with a valve J, and below this valve the chamber is provided with a piston ring K of rubber, leather, or other suitable packing material adapted to form a water and air tight joint, to prevent air 55 from passing downwardly in the well tube A, around the chamber F and, of course,

also adapted to prevent water from passing upwardly in this space.

Below the annular packing, and below the chamber F, I preferably provide the 60 well tube A with a cross rod L, adapted to limit the downward movement of chamber F, while allowing said chamber to be lowered into close proximity to the tapered point B.

Air under pressure is supplied from any suitable source of supply, through a duct M, which may enter the well tube A at any desired point, filling the well tube with compressed air, and forcing any water that 70 may be therein out of the space above the tubular chamber F through the duct H. The chamber F, will, of course, be full of water which enters the chamber past the valve J, the water rising normally in the 75 pipe D to the level which it naturally assumes in the well.

Therefore, when the compressed air M is delivered into the well tube, it will eventually pass out through the duct H, and its 80 nozzle I underneath the column of water in the tube D. The water will therefore be blown out of the tube D, and the air will exert an aspirating effect, drawing additional water from the chamber F. The 85 chamber F will then be constantly refilled by water entering past the valve J, and if the water supply is sufficient, as derived from the strata in which the well is located, the ejector may be operated continuously for the delivery of water through the pipe D.

At the top of the pipe D, (i. e., at the top of the well) I preferably deliver the water into a separating chamber O of sufficient size 95 as to allow the water to become comparatively quiet, whereupon the air will rise to the upper portion of the chamber. A pipe Q may lead from the bottom of this chamber, and constitute the service pipe for supplying water to a building, or it may be connected with such a service pipe as may be desired.

By providing a float valve in this tank, and utilizing the valve to control deliveries 105 through the pipe D, it is possible to shut off water delivery whenever a predetermined water level is reached in the tank. A blow-off valve R may be employed to permit air delivery from the tank, and regulate the 110 pressure within the tank. Under these conditions, the air pressure may be constantly

maintained within the well, by means of the pipe M, and water delivery controlled entirely by said float operated valve.

I claim:—

- 5 1. The combination with an air tight well tube, of a tubular chamber in the lower portion thereof, in air tight relation to the well tube, said chamber being provided with a valved water inlet at its lower end, opening upwardly in said chamber, a water outlet duct leading from the upper portion of said chamber, an aspirating duct leading through the top wall of said chamber, and provided with a nozzle outlet in the water discharge duct, and means for supplying air under pressure to the well tube above said chamber, whereby the use of a separate air tube may be dispensed with, and the suction developed by the aspirating duct utilized to draw water into the lower end of the well tube.
- 10 2. The combination with an air tight well tube, of a tubular chamber in the lower portion thereof, in air tight relation to the well tube, said chamber being provided with a valved water inlet at its lower end, opening upwardly in said chamber, a water outlet duct leading from the upper portion of said chamber, an aspirating duct leading through the top wall of said chamber, and provided with a nozzle outlet in the water discharge duct, a support for said chamber connected with the lower end portion of the well tube, and means for supplying air under pressure to the well tube above said chamber, whereby the use of a separate air tube may be dispensed with, and the suction developed by the aspirating duct utilized to draw water into the lower end of the well tube.
- 15 3. The combination with a well tube, of a water discharge tube leading downwardly therein, an air nozzle in the lower end of

said water discharge tube, means for supplying air under pressure to the upper portion of the well tube, together with a water chamber for the discharge tube adapted to fit in the well tube in air tight relation thereto to prevent air pressure from being exerted upon the water below the chamber, and provided with an inwardly opening valve at its lower end, and a connection between the air nozzle and the well tube above the water chamber.

4. The combination with a well tube, of a water discharge tube leading downwardly therein, a water chamber connected with the lower end thereof, and provided with a valved inlet, an air nozzle leading downwardly through the top of the water chamber, and having an upwardly projecting outlet portion within the water discharge tube, means for supplying air under pressure to the well tube above the water chamber, a separating chamber in combination with the discharge end of the water outlet tube, and provided with a blow off valve for air delivery from its upper portion, and a service pipe connected with the lower portion of the separating chamber, said separating chamber being located above the well tube, and said water chamber within the well tube being provided with a packing ring adapted to prevent access of air to the lower end of the well tube below the water chamber, whereby water may be drawn into the well tube and said chamber under nozzle suction at less than atmospheric pressure.

In testimony whereof I affix my signature in the presence of two witnesses.

BURDETT P. HOPKINS.
